BULLET-RESISTING STRUCTURE

Charles D. O'Kieffe, Minneapolis, Minn., assignor
to O. B. McClintock Company, Minneapolis,
Minn., a corporation of Minnesota

Application August 9, 1933, Serial No. 684,318

11 Claims.

(Cl. 89—36)

This invention relates to a bullet-resisting structure for the exposed side or sides of a cage or similar enclosure to protect the person or persons in the enclosure as well as the valuables in his possession from a daylight hold-up bandit.

The object of this invention is to provide a bullet-resisting structure with novel voice or sound openings through which persons on opposite sides of the structure may converse in ordinary tones. While these voice openings permit free travel of sound therethrough they cut off a direct opening or openings in the structure through which a bullet may be fired.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a fragmentary front elevation showing one form of the improved bullet-resisting structure;

Fig. 2 is a view in vertical section taken on the line 2—2 of Fig. 1;

Fig. 3 is a view in horizontal section taken on the line 3—3 of Fig. 1;

Fig. 4 is a fragmentary detail view in horizontal section taken on the line 4—4 of Fig. 1;

Fig. 5 is a view principally in rear elevation of the parts shown in Fig. 1;

Fig. 6 is a perspective view of one of the lower metal panels removed from the structure;

Fig. 7 is a fragmentary perspective view of one of the horizontal rails and one of the seats for the respective upper glass panel, the side member of said seat being segregated; and

Figs. 8, 9, 10, 11 and 12 are fragmentary views in horizontal section showing various modifications of the bullet-resisting structure.

The numeral 12 indicates a counter which forms part of a teller's cage or enclosure in a banking room or the like and which counter extends to the floor and has a relatively wide top. This counter 12 if made of wood or other non-bullet resisting material will be lined or otherwise reinforced with a bullet-resisting material, not shown.

Mounted on the counter 12 is a bullet-resisting partition or structure which includes a frame comprising posts 13, bottom rails 14, top rails 15 and intermediate rails 16. This structure further includes lower metal panels 17, upper glass panels 18, and a wicket 19. The lower panels 17 are mounted between the posts 13, the bottom rails 14 and the intermediate rails 16, and the upper panels 18 are mounted between the posts 13, the top rails 15 and the intermediate rails 16. Between two of the posts 13, the bottom rail 14

is omitted and the wicket 19 is mounted in the space between said posts. It will be noted that the intermediate rail 16, above the wicket 19 is relatively close to the overlying top rail 15 and that the other intermediate rails 16 are relatively close to the bottom rails 14.

The wicket 19 includes a glass insert 20, a voice panel 21 on each side of said insert, a deal tray 22, gun ports 23, and a voice panel 24 between the insert 20 and the deal tray 22. It may be here stated that the panels 18 and insert 20 are each formed, as shown, from a single piece of bullet-resisting glass.

The construction of the posts 13, the rails 14, 15 and 16 and the mounting of the panels 17 and 18 therein is such as to leave voice or sound openings that extend through said posts and rails at and around the perimeters of the panels 17 and 18. These voice or sound openings not only permit persons on opposite sides of the structure to converse in ordinary tones but they also permit a free circulation of air from one side of the structure to the other. Each rail 14, 15 and 16 is fabricated and includes a horizontal channel bar 25, a face plate 26 and a back plate 27 secured to the outer and inner flanges of said bars, respectively. By reference to Fig. 2 it will be noted that the channel bars 25 of the bottom rails 14 and intermediate rails 16 are inverted.

Each post 13 is also fabricated and includes a vertical tie-rod 28 and the tie-rods of the several posts 13 extend through aligned holes in the top of the counter 12 and the webs of the channel bars 25 of the several rails 14, 15 and 16. The intermediate rails 16 and the top rails 15 are held vertically spaced from each other and from the bottom rails 14, which rest on the top of the counter 12, by spacing sleeves 29 telescoped onto the tie-rods 28. Washers and nuts 30 applied to the ends of the tie-rods 28 anchor said rods to the counter 12 and hold the channel bars 25 and spacing sleeves 29 clamped together.

Each post 13 further includes a face plate 31 and a back plate 32 secured to the outer and inner flanges of said bars, respectively. Formed with the upper edges of the back plates 32 of the bottom rails 14 and the intermediate rails 16 are inturned baffles 33 and like baffles, having the same reference numeral, are formed on the lower edges of the back plates 32 of the top rails 15 and the back plates 32 of the posts 13.

The panels 17 are secured by screws 34 and apertured lugs 35 to the channel bars 25 of the bottom and intermediate rails 14 and 16, respectively, and said lugs 35 are formed with the upper and lower edge portions of the panels 17 at the corners thereof. On the vertical edges of the panels 17 are laterally and inwardly projecting flanges that afford baffles 36. The panels 17, at

their upper and lower edge portions, are cut away to form voice or sound openings 37. It is important to note that the panels 17 and 18 at their perimeters, extend into the posts 13 and rails 14, 15 and 16, are spaced therefrom to form circuitous passages through said posts and rails and around the panels. These circuitous passages lead from one side of the structure to the other and cut off direct openings therethrough.

10 The width of the baffles 36 is substantially the same as the thickness of the glass panels 18 and the purpose thereof is to reduce the space between the face and back plates of the posts 13 and leave openings of substantially the same 15 width as between said glass panels and the respective face and back plates. Each panel 18 is removably mounted in four recessed lugs 38 secured to the channel bars 25 of the top rails 15 and intermediate rails 16. These lugs 38 hold 20 the panels 18 against movement in all directions and each lug 38 has a removable side, see Fig. 7. As shown, each panel 18 is mounted in a rectangular metallic frame 39 that is channel-shaped in cross-section but if desirable, this frame may 25 be dispensed with.

10 The wicket 19 is held in place by lugs 40 with its vertical edge portions extending into the adjacent posts 13 and its upper horizontal edge portion extending into the overlying intermediate rail 16 and which wicket is laterally spaced from the respective face and back plates. The spacing of the wicket 19 in the posts 13 and the respective rail 16 is such as to form circuitous passages therethrough. These circuitous passages lead 30 from one side of the structure to the other and cut off direct openings therethrough.

Obviously, the panels 18, wicket 19, spacing sleeves 29, and baffles 36 cut off direct passages obliquely through the posts 13 from one side of the structure to the other and the channel bars 25 cut off direct passages obliquely through the rails 14, 15 and 16 from one side of the structure to the other. The baffles 36 on the posts 13 and the rails 14, 15 and 16 prevent bullets from ricochetting when fired into said posts or rails from 45 the front of the structure.

10 In the structure shown in Fig. 8 the numeral 41 indicates a bullet-resisting partition having a wicket opening 42 over a counter, not shown, and in which opening is mounted a wicket 43 comprising two hollow posts 44 and a transparent insert 45 of bullet-resisting glass therebetween. The opposing faces of the two posts 44 are open and the outer sides thereof are in substantially the same plane while the inner sides thereof are in 50 outwardly converging relation. The vertical edge portions of the insert 45 extend into the posts 44 at their open faces substantially midway between the sides thereof. This mounting of the insert 45 laterally offsets the same toward the inside of the partition 41, thus leaving considerable 55 space on the counter in front of the wicket 43 for a customer.

10 The mounting of the insert 45 with its vertical edge portions extending into the posts 44, at their open faces, forms circuitous voice or sound passages through the posts 44 that cuts off direct openings therethrough from one side of the partition 41 to the other. The glass insert 45 is mounted in a rectangular metal frame 46 that is 60 channel-shaped in cross-section but in some instances it might be desirable to dispense with this frame.

10 A lining 47 of sponge rubber or other relatively soft material is applied to the inner surfaces of

the back and inner side of each post 44 to prevent a bullet fired into said post from the front thereof from ricochetting. The exposed surfaces of the lining 47 are covered with sheet bronze 48 or other suitable material. On the outer vertical edges of the inner side of each post 44 is a flange-like baffle 49 that projects toward the insert 45. The purpose of the baffles 49 is to further prevent bullets fired into the posts 44 from the front thereof from ricochetting.

10 The openings between the backs of the posts 44 and the vertical edges of the insert 45, at the front thereof, are each covered with a grill 50 and the openings between the baffles 49 and the inner sides of the insert 45 are each covered with a grill 51.

10 As shown, the face plates of the several posts and rails are formed from extruded metal to reinforce the same and give the frame structure an artistic appearance. The wicket 52, shown in Fig. 9, is the same as the wicket 43 except the glass insert 53 is not mounted in a frame.

10 Referring now to the wicket 54, shown in Fig. 10, the numeral 55 indicates a bullet-resisting partition having a wicket opening 56 in which 25 the wicket 54 is mounted. This wicket 54 includes two hollow posts 57, only one of which is shown, and a transparent insert 58 formed from a piece of bullet-resisting glass mounted between said posts. Each post 57 is square in 30 cross-section and the opposing faces of the two posts 57 are open.

10 The insert 58 is mounted in a metallic frame 59 that is channel-shaped in cross-section and which frame extends outwardly from the face 35 of the post 57 midway between the sides thereof. A grill 60 covers the opening between the outer side of the post 57 and the outer face of the frame 59.

10 In Fig. 8 additional space on the counter, in front of the wicket 43, is obtained by distorting the posts 44 to offset the insert 45 and additional space on the counter, in front of the wicket 54 is obtained by bodily inwardly offsetting the posts 44 with respect to the partition 55.

10 Fig. 11 shows a novel post 61 between two panels 62 which, as shown, are each formed from a piece of bullet-resisting glass. This post 61 includes two upright channel bars 63, the backs of which are turned toward each other and laterally spaced. The two panels 62, which are in the same plane, have their adjacent vertical edge portions mounted in the channel bars 63. Directly back of the post 61 on the inside of the structure is a baffle 64 in the form of a wide and shallow upright channel bar that extends transversely of the bars 63 and is laterally spaced therefrom. The baffle 64 is directly back of the opening between the bars 63 and extends for a considerable distance on each side thereof with 50 its flanges turned toward the post 61. The spaces between the bars 63 and between the said bars and the baffle 64, form a circuitous voice or sound passage that extends from one side of the panels 62 to the other and cuts off a direct 55 opening therethrough.

10 The bullet-resisting structure shown in Fig. 12 is substantially the same as that shown in Fig. 11, with the exception that the channel bars 65 of the posts 66 are spaced farther apart and a second baffle 67 is mounted therebetween. In this structure the baffle, which corresponds to the baffle 64, and the glass panels are designated by the numerals 68 and 69, respectively. The 70 75

baffle 67 is T-shaped in cross-section and its body extends toward the baffle 68.

From the above description it is evident that all of the voice or sound openings through the posts and rails of the frame structure cut off direct openings that lead from one side of the structure to the other and prevent a bullet from being fired therethrough.

In the structure shown in Figs. 1 to 10, inclusive, the panels whether mounted in a frame or not act as baffles that cut off direct openings through the posts and rails of the frame structure.

If a bullet is fired into either of the posts 44, it will be embedded in the relatively soft material 47 which prevents the same from ricochetting.

What I claim is:

1. A structure of the class described having a member provided with a circuitous voice passage leading from one side of the structure to the other and cutting off a direct opening therethrough, and a thick relatively soft non-metallic material in said member at one side of the passage.

2. The structure defined in claim 1 which further includes a thin relatively soft metal covering for said non-metallic material.

3. A structure of the class described comprising a post member, a pair of top rails and a pair of bottom rails, said pairs of rails having at one of their ends apertures through which the post member extends, a spacing device on the post member holding the rails of the top pair spaced above the rails of the bottom pair, a panel mounted between the rails of each pair and held thereby, the panels at one of their vertical edges being spaced from the post member to leave a voice opening between the post member and each panel, and a plate spaced outwardly of the post member and the panels and cutting off a direct passage through the voice openings.

4. A structure of the class described comprising a post member, a pair of top rails and a pair of bottom rails, said pairs of rails having at one of their ends apertures through which the post member extends, a spacing device on the post member holding the rails of the top pair spaced above the rails of the bottom pair, a panel mounted between the rails of each pair and held thereby, the panels at one of their vertical edges being spaced from the post member to leave a voice opening between the post member and each panel, and a plate on each side of the post member and the panels and cutting off a direct passage through the voice openings from either side of the structure.

5. A structure of the class described comprising a post member, a top rail and a bottom rail secured to the post member, a panel between the rails and held thereby, said panel at one of its vertical edges being spaced from the post member to leave a voice opening therebetween, and a plate spaced outwardly of the post member and the panel and cutting off a direct passage through the voice opening.

6. A structure of the class described comprising a post member, a top rail and a bottom rail secured to the post member, a panel between the rails and held thereby, said panel at one of its

vertical edges being spaced from the post member to leave a voice opening therebetween, and a plate on each side of the post member and the panel spaced outwardly thereof and cutting off a direct passage through the voice opening from either side of the structure.

7. A structure of the class described comprising a post member, a pair of top rails and a pair of bottom rails, the rails of each pair at one of their ends being secured to the post member, a panel 10 between the rails of each pair and held thereby, the panels at one of their vertical edges being spaced from the post member to leave voice openings therebetween, and a plate spaced outwardly of the post member and the panels and cutting off 15 a direct passage through either of the voice openings.

8. A structure of the class described comprising a post member, a pair of top rails and a pair of bottom rails, the rails of each pair at one of their 20 ends being secured to the post member, a panel between the rails of each pair and held thereby, the panels at one of their vertical edges being spaced from the post member to leave voice openings therebetween, and a plate on each side of the 25 post member and panels, spaced outward thereof and cutting off a direct passage through the voice openings from either side of the structure.

9. A structure of the class described including a hollow post having an open face, and a panel 30 extending at one of its edge portions into the post at its open face and spaced from the internal surfaces of said post to leave a voice opening between the post and the panel, said panel cutting off a direct opening through the structure 35 between the post and the panel, and an open mesh screen in the voice opening.

10. A structure of the class described including a hollow post having an open face, a panel extending at one of its edge portions into the post 40 at its open face substantially midway between the sides of the post and spaced from the internal surfaces of the post to leave a voice opening between the post and the panel, one of the sides of the post being in outwardly diverging relation 45 to the plane of the panel and cutting off a direct opening through the structure between the post and the panel, and a non-metallic means in the post on the back and diverging side thereof to prevent a bullet fired into the post from ricochetting.

11. A structure of the class described including a partition having a wicket opening, a counter below said opening, and a wicket in the opening comprising two hollow posts, the opposing faces 55 of which are open, and a transparent insert between the posts extending into the open faces thereof substantially midway between the sides of the posts and cutting off direct openings between the posts and the insert, one of the sides 60 of the posts being in outwardly diverging relation to the plane of the partition and in relative converging relation, said diverging sides laterally offsetting the insert from the plane of the partition to increase the working space on the counter on the opposite side of the insert from the converging sides of the posts, said insert being spaced from the internal surfaces of the posts to leave voice openings between the posts and the insert.
